UNITED STATES PATENT OFFICE.

JAMES EINAR BROWN, OF LARAMIE, WYOMING.

DESIGN FOR A FLAGPOLE.

Application filed June 11, 1921. Serial No. 476,947. Term of patent 14 years.

To all whom it may concern:

Be it known that I, JAMES EINAR BROWN, a citizen of the United States, and residing at Laramie, in the county of Albany and State of Wyoming, have invented a new, original, and ornamental Design for a Flagpole, of which the following is a specification, reference being had to the accompanying drawings, forming a part hereof.

The figure is a perspective view showing my new design for flagpole.

I claim:—

The ornamental design for a flagpole, as shown.

JAMES EINAR BROWN.
